The ornamental design for an outdoor emergency power supply, as shown and described.

DESCRIPTION

FIG. 1 is a front, top and right side perspective view of an outdoor emergency power supply, showing my new design; FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 shown in FIG. 1. The dash-dash broken lines in the drawings illustrate portions of the outdoor emergency power supply. The dot-dash broken lines in the drawings illustrate the boundaries of the enlarged views. None of these broken lines form part of the claimed design.
